UNITED STATES PATENT OFFICE.

PIERRE PLANTINGA, OF CLEVELAND, OHIO.

OVEN-WALL STRUCTURE.

Application filed May 1, 1920. Serial No. 378,234.

To all whom it may concern:

Be it known that I, PIERRE PLANTINGA, a citizen of the United States, resident of Cleveland, county of Cuyahoga, and State of Ohio, have invented new and useful Improvements in Oven-Wall Structures, of which the following is a specification, the principle of the invention being herein explained and the best mode in which I have contemplated applying that principle, so as to distinguish it from other inventions.

My invention relates to oven wall structures, and particularly to a new and improved construction of the jambs thereof. The object of the invention is to design a jamb structure in which high-temperature-resisting elements may be utilized for the interior, combined with oven wall face elements which will not spall when the cold air strikes them, together with the features which will overcome the difficulty heretofore experienced because of the separation under great heat at the joint between the high-temperature-resisting elements and the non-spalling elements.

The annexed drawing and the following description set forth in detail certain means embodying my invention, the disclosed means, however, constituting but one of the various mechanical forms in which the principle of my invention may be applied.

In said annexed drawing:

Figure 1 represents a fragmentary plan section of a coke oven embodying my new and improved jamb construction;

Figure 2 represents a vertical longitudinal section taken in the plane indicated by the line II—II, Figure 1.

Figure 3 represents, upon an enlarged scale, a fragmentary plan section of one of the flues shown in Figure 1 and taken in the plane indicated by lines III—III, Figure 4;

Figure 4 represents a longitudinal, vertical section taken in the plane indicated by the line IV—IV, Figure 3;

Figure 5 represents a fragmentary plan section taken in the plane indicated by the line V—V, Figure 4;

Figure 6 represents a fragmentary, transverse, vertical section taken in the plane indicated by the line VI—VI, Figure 3;

Figure 7 represents a view similar to that of Figure 6, but illustrating the several positions assumed by the jamb bricks when the oven wall has expanded;

Figure 8 represents a vertical, longitudi-

nal section similar to Figure 2, showing the condition obtaining under the present jamb construction when the wall has expanded, which it is the purpose of my invention to obviate; and

Figures 9 and 10 represent front perspective and rear perspective views of a special jamb facing brick entering into my construction.

Referring to the annexed drawing, a pair of oven walls are indicated by the ordinal 1, forming between them the usual coking chamber 2, having a jamb face 3, the other end of the coke oven, not shown, being of the same construction as the end shown. The ordinal 4 indicates a customary cast iron plate covering the oven face and intended for the protection of the jamb. Access to the coking chamber 2 is obtained through the medium of the usual door 5. These oven walls 1 are formed of silica bricks interlocked in the manner plainly shown in Figure 5. Transverse anchoring bricks suitably distributed are indicated by the ordinal 6. In the present construction of oven walls, the jamb is formed of fire clay because it is impossible to utilize silica the entire distance to the opening or jamb of the oven, inasmuch as it will spall when the cold air strikes it.

However, great difficulty is experienced at the joint between the silica walls and the clay jambs because the silica expands considerably when the oven is brought up to working temperature, such expansion amounting to from $\frac{1}{8}$ to $\frac{1}{16}$ of an inch per foot, which totals in an oven of the standard ten foot height, from one to two inches of expansion. The ordinary clay materials, on the other hand, expand very slightly. The result is a tendency to tilt the clay jamb, break the bond between the bricks, opening up cracks through which gas or air can pass, and distorting the support for the roof 14.

This condition is plainly indicated in Figure 8, wherein it will be noted that there is an increasing differentiation from bottom to top between the alignment of the jamb facing 8' and the several silica bricks, $1'$, $1\frac{1}{2}'$, $1\frac{3}{4}'$, $1\frac{1}{4}'$, etc., to the rear thereof, until at the top the accumulated expansion has resulted in a considerable opening 16, resulting in the deleterious effects hereinbefore mentioned. In my improved jamb, I have formed the same of a silica material central portion and clay material facings. This is plainly indicated in Figure 6, for instance. It will

be noted, also, that the silica bricks 7 forming the central portion of the jamb are of two sizes, are of greater cross section in one plane than in a transverse plane, and are alternately arranged so as to present first the broad side of a brick 7 and then the narrow end of a brick 7'. The same size bricks might be used for both courses by arranging them with the broad sides to the front and the narrow sides to the front alternately. The clay facing bricks 8 are of a length equal to two courses of silica bricks, the upper portion 9 thereof lying adjacent a silica brick which is presented broad side to the face of the oven, and the lower portion 10, of comparatively increased cross section, Figures 9 and 10, lying adjacent a silica brick presenting a narrow end to the face of the oven, such enlarged portion 10 of the clay brick lying intermediate two of the aforementioned broad side silica bricks. This detailed arrangement of the several silica bricks 7 and 7' and the clay brick portions 9 and 10 is one way of interlocking the silica and clay so that there is no opportunity for an accumulated expansion of the whole wall, but such expansion must express itself in small amounts between the several bricks. In other words, inasmuch as the clay bricks 8 are only two courses high, about ten inches, each joint will open up not to exceed $\frac{1}{16}$ of an inch. This is illustrated by ordinal 13, Figure 7. The clay facing bricks are formed with co-operating tongues 11 and grooves 12, whereby they are severally interlocked. As plainly indicated in Figure 7, these tongues and grooves take care of the slight expansion of the joint between the several silica and clay bricks. It is not necessary to care for this expansion by such special means as these tongues and grooves, but the same are beneficial in this respect. The several joint openings of $\frac{1}{16}$ of an inch each or so would also carbon up, thus taking care of these openings without the necessity of the special tongues and grooves. As plainly indicated in Figure 5, the clay facing bricks 8 are interlocked with the front silica bricks of the walls 1, and the several silica bricks of the walls 6 are also interlocked with tongues and grooves.

What I claim is:

1. A jamb construction for oven walls consisting of high-temperature-resisting elements interlocked with ceramic elements

which are non-spalling when subjected to cold air.

2. A jamb construction for oven walls consisting of high-temperature-resisting elements forming the central body portion 60 thereof and ceramic elements which are non-spalling when subjected to cold air forming the side body portions thereof.

3. A jamb construction for oven walls consisting of silica material forming the 65 central body portion thereof and clay material forming the facings.

4. A jamb construction for oven walls consisting of silica bricks forming the central body portion thereof and clay bricks 70 interlocked with said silica bricks and forming the facings.

5. An oven comprising a pair of front walls of silica and forming between them a coking chamber, combined with jambs 75 formed of silica except that the facings of the front walls forming the sides of the jambs are formed of clay material.

6. An oven comprising a pair of front walls of silica and forming between them a 80 coking chamber, combined with jambs formed of interlocked silica and clay bricks, of which the facings of the front walls forming the sides of the jambs are clay bricks.

7. A jamb construction for oven walls consisting of silica bricks forming the central body portion thereof and clay bricks forming the facings of the fronts of the adjacent oven walls, the silica bricks being greater in cross-section in one plane than in a transverse plane and laid with alternate bricks on edge, and the clay bricks having extensions or enlargements respectively disposed adjacent alternate silica bricks and intermediate the silica bricks above and below said alternate bricks.

8. An oven comprising a pair of front walls of silica and forming between them a coking chamber, combined with jambs 100 formed of interlocked silica and clay bricks, of which the facings of the front walls forming the sides of the jambs are clay bricks, the adjacent surfaces of said facing bricks being respectively formed with interlocking 105 tongues and grooves.

Signed by me, this 28th day of March, 1920.

PIERRE PLANTINGA.
